UNITED STATES PATENT OFFICE.

HELEN SINGER, OF NEW YORK, N. Y.

BOUDOIR-LAMP.

1,211,771.

Specification of Letters Patent. Patented Jan. 9, 1917.

Application filed November 24, 1915. Serial No. 63,180.

To all whom it may concern:

Be it known that I, HELEN SINGER, a citizen of the United States, and a resident of New York city, in the county of New York 5 and State of New York, have invented certain new and useful Improvements in Boudoir-Lamps, of which the following is a specification.

This invention relates to certain improvements in lamps and more particularly to the means for supporting and shading an electric light bulb and at the same time providing an attractive ornament for a table or dresser.

15 My improved lamp in its preferred construction includes a base upon which is mounted not only the light but also a doll, the skirt of the latter serving as the shade for the light. The light as well as all or substantially all of its standard is normally concealed from view so that when the light is turned off, the device to the casual observer appears to be merely a doll supported by the base.

25 Various changes may be made in the details of construction and the arrangement of parts without departing from the spirit of my invention as defined in the appended claims.

30 Reference is to be had to the accompanying drawings which show merely one embodiment of my invention and in which similar reference characters indicate corresponding parts in the several views.

35 In these drawings: Figure 1, is a front elevation of a device constructed in accordance with my invention; and Fig. 2, is a central vertical section of the lower portion.

In the preferred form illustrated, the device 40 includes a base 10, of any suitable character the size of which is as small as is practical, to provide the necessary stability to the device. Superposed on the base 10 is a plate 11, preferably of sheet metal and having at one edge thereof a vertical extending arm 12. This arm may be formed integral with the plate 11 and may be bent to tubular or channel shape to give it rigidity and to facilitate its telescopic connection with the body of the doll or a portion carried by said body. As illustrated, the plate 11, is of substantially the same size as the top of the base so as to render its edges less conspicuous.

45 Extending upwardly from the center of the base is a standard 13, to the upper end

of which may be secured a small electric light bulb 14. The standard 13 may have an outwardly extending flange at its lower end which may be secured to the plate 11, 50 and to the base 10 by screws or bolts 15 so that the same screws or bolts which connect the standard to the plate will also connect the latter to the base. In other words, the plate 11 may be clamped between the lower 55 end of the standard 13 and the base so as to avoid the necessity for separate securing means for connecting the plate and base.

As a shade for the light, I provide a doll having a body portion 16 supported above 70 and preferably slightly in the rear of the bolt. The doll's body 16, has a depending arm 17, rigidly secured thereto and adapted to telescope with or be secured to the upwardly extending arm 12 of the base. As 75 illustrated, the depending arm 17 is in the form of a loop of wire the ends being firmly secured to the body and the loop portion extending into the end of the arm 12. The doll may be readily removed from the base 80 but the resiliency of the wire provides sufficient frictional engagement with the arm 12 to effectively hold the body 16 in position. The telescoping parts 12 and 17 are of such 85 length that the legs 18 of the doll may extend downwardly at each side of the bulb and its support and the feet of the doll may rest upon or come closely adjacent to the upper surface of the base. Secured to the body of the doll is a skeleton frame 19, which 90 may include a series of superposed spaced rings 20 and connecting strips 21. The lowermost ring is of the largest size while the superposed ring or rings are of decreasing diameter. The rings need not be absolutely rigid but are made of sufficiently stiff material to normally hold their shape. The upper ends of the strips 21 may be secured to the body 16 in any suitable manner as, for instance, by being connected to a tape 22 100 tied about the waist of the body. Outside of this skeleton frame is the main lamp shade 23 which serves as a skirt for the doll and which may be of any suitable material, preferably trimmed to give it an ornamental 105 appearance. The skirt is made very full and is held out away from the light by the skeleton frame so that the material of the skirt is prevented from coming into too close engagement with the light. The shape of the 110 frame is such that it holds the skirt in the form of a substantial bell shaped lamp shade,

The doll's body comes behind the electric light while the leg portions come at the sides. Thus these parts do not tend to cast any shadow on the front portion of the skirt 5 which is normally presented to view. By making the lower end of the body and the legs of white and smooth, shiny or glazed material, the light rays striking them will be reflected forwardly and the effective 10 illuminating power of the lamp as seen from the front will be correspondingly increased. The body and legs of the doll may be made of noncombustible material. With the ordinary construction of doll I preferably use 15 a shield or screen 24 behind the light and in front of the doll parts so as to protect the latter and reflect both the heat and the light forwardly. This shield may be of asbestos or other similar noncombustible material 20 and may extend above as well as behind the light and be secured to the doll or to the standard or socket of the lamp. Preferably the standard is somewhat shorter in respect to the size of the doll than is shown in the 25 drawing.

The lamp may be connected to a source of electrical energy and the current controlled in any suitable manner. As a simple and inconspicuous arrangement, I extend 30 the wires through an aperture in the rear side of the base and in the rear of the arm 12, and extend them up through the standard 13. A suitable switch may be mounted in the standard 13 or directly at the lower 35 end of the bulb. As shown, the switch is provided with a short flexible controlling member 25 extending downwardly to the base so as to facilitate the operation of the switch.

Having thus described my invention, what I claim as new and desire to secure by Letters Patent is:

1. A lamp including a base, a plate sup-

ported thereon and having an upwardly extending arm integral therewith, a lamp 45 standard on said plate, means for connecting said standard, plate and base together, a body portion having a depending arm telescoping with said first mentioned arm, a skeleton frame including a series of concentric spaced rings supported by said body portion, and a lamp shade shaped cover encircling said frame.

2. A lamp including a base, a plate supported thereon and having an upwardly extending arm integral therewith, a lamp 55 standard on said plate, means for connecting said standard, plate and base together, a body portion having a depending arm telescoping with said first mentioned arm, a 60 skeleton frame including a ring larger than and suspended from said body portion, a lamp shade shaped cover encircling said frame, and a shield of non-combustible material supported beneath said shade and between said body portion and said light.

3. A lamp including a base, an upwardly extending arm carried thereby, a lamp standard carried by said base, a doll body having a depending member telescoping 70 with said upwardly extending arm, a skeleton frame secured to said body and including a series of concentric spaced rings and flexible connecting members, a lamp shade shaped cover encircling said frame and having its lower edge spaced above said base, and a non-combustible shield supported beneath said cover and between the lamp and 75 said doll body.

Signed at New York city, in the county of 80 New York, and State of New York, this 19th day of November, A. D. 1915.

HELEN SINGER.
